UNITED STATES PATENT OFFICE

2,613,595

REVOLVING MULTIPLE COLOR SCREEN
PROCESS PRINTING TABLEJoseph T. Weldon, New York, N. Y., assignor, by
mesne assignments, to Multiscreen Corporation,
New York, N. Y., a domestic corporation

Application January 5, 1950, Serial No. 136,950

2 Claims. (Cl. 101—115)

1

This invention relates to improved apparatus for the printing on fabrics, paper or similar material by means of the silk screen process.

Such printing is accomplished by fixing the fabric to be printed upon on a suitable surface, lowering the silk screen thereon and then transferring the color thereto by means of a roller or squeegee. Where several colors are to be printed on the fabric, several silk screens are used successively.

One object of the invention is the provision of apparatus whereby in one operation of said squeegee the colors from a plurality of screens are transferred each to one of a like plurality of fabric pieces or the like so that, for example, if three colors are being used, three fabric pieces have all three colors printed thereon in three operations of the squeegee.

A further object of the invention is the provision of means for accurately locating the screens relative to the fabric pieces rapidly and accurately.

Still another object of the invention is to construct the device so that the fabric pieces are located on a plurality of platforms arranged in a circle and rotatable about a fixed base on which is hinged the screen means.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the device in normal position.

Fig. 2 is a perspective view of the device with the screen means in the process of being lowered to printing position.

Fig. 3 is a side elevation of the device as shown in Fig. 2.

Fig. 4 is a perspective view of the device with the screen means in printing position.

Fig. 5 is a front elevation of the device as shown in Fig. 4.

Fig. 6 is a plan view of the device with the screen means removed.

Fig. 7 is a sectional view on line 7—7 of Fig. 6 but with the screen means also shown.

Fig. 8 is a sectional view on line 8—8 of Fig. 7.

Fig. 9 is a fragmentary enlarged detail view of the screen locating means shown also in Fig. 5.

Fig. 10 is a detached detail view of a multiple roller utilized in printing.

The apparatus for printing on fabrics, according to the present invention, includes a circular bed plate 15 mounted on legs 16 and having centrally secured to its upper face a circular

2

stepped block 17. The block is secured in position by several spaced screws 17^a, see Figs. 7 and 8. Loosely journaled on the reduced portion of the stepped block 17 and resting on the step 18 thereof is a revolving table 20, said table also receiving support from a plurality of blocks 21 fixed to the upper face of bed plate 15 adjacent its periphery (see also Figs. 3, 5, 7 and 8). The table 20 is rotatably retained on the step 18 and blocks 21 by a triangularly shaped member 22 fastened to the stepped block 17.

The triangularly shaped member 22 is comprised of a center arm 22^a and a pair of converged side arms 22^b and is secured to the stepped block 17 by several screws 22^a, see Figs. 6 and 7. The triangularly shaped member 22 may be made of wood, metal or may be molded of any desired synthetic resinous plastic material.

Fixed to the upper face of table 20 near the periphery thereof, and arranged radially, are a large plurality of printing platforms 23 on which pieces of fabric 24 (Fig. 1) are secured in any suitable way such as by gluing. Instead of separate platforms 23, there could be secured to the top face of the table 20 a single ring-shaped disc upon which the pieces of fabric 24 could be mounted.

The mount for the printing means comprises a triangular block 25 (Figs. 1, 2, 4 and 7) secured atop the bars 22. A bar 26 is longitudinally pivoted to one edge of block 25 by a hinge 27 (see also Fig. 3) and has secured thereto by a second bar 28 a printing frame 30 comprising in the present instance longitudinal frame bars 31 and end bars 32. The frame 30 is divided into three sections by a pair of partition bars 33, and each section has secured therein in the manner usual with such devices a silk screen 34. For clarity of description the three screens are differentiated by the letters *a*, *b* and *c* affixed to the reference numeral 34. Normally the frame 30 is held in an upwardly inclined position, as shown in Fig. 2, by a pair of springs 36 affixed to a block 35 and to the side bars 32 of the frame. The block 35 is secured to the top face of the block 25 by several screws 35^a, see Fig. 7.

The triangular block 25 is secured to the triangularly shaped member 22, by screws 25^a, see Figs. 2 and 4, which are threaded into complementary holes 25^b formed in the converged outer arms 22^b of the triangular member 22, see Fig. 6.

The construction is such that the frame 30 is normally in the position of Fig. 1 as just described, but can be moved down over the platforms 23 by hand as shown in Figs. 2 and 4. The platforms 23, being mounted on the table 20, are rotatable so that any desired one of the platforms can be located under the center section screen 34^b of the printing frame, the adjacent platforms then being located under the screens

^{34a} and ^{34c}. Thus, if a three-colored pattern is to be printed on the fabric pieces ²⁴ secured on said platforms, each of the screens ³⁴ may be provided with the desired pattern of one coloring agent. For example, each of the screens is provided with a ring ³⁷ of a different color to provide a pattern of three differently colored interwoven rings such as indicated at ³⁸ (Fig. 1). The rings ³⁷ are, of course, differently located on the screens ³⁴ to take into account the varied positions thereof above the platforms ²³. To print pattern ³⁸ the frame ³⁰ is lowered, as described above, and an ordinary roller ⁴⁰ (Fig. 10) rolled over each of the screens ³⁴ to transfer the color to the fabric ²⁴. The table ²⁰ is then rotated to bring the platform previously under screen ^{34a} under screen ^{34b}, and that platform under ^{34c}, and so on until all of the patterns ³⁸ are completed.

In order to simplify and expedite the operation of rolling the screens ³⁴, a multiple roller ⁴¹ having annular recessed portions ⁴² to accommodate the partition bars ²³ may be utilized to roll all three screens ³⁴ at once.

In order to insure the correct positioning of the frame ³⁰ above the several platforms ²³, each of the latter has projecting from its outer edge a nail or pin ⁴³ which, as the frame ³⁰ is lowered, is engaged and cammed to the correct position (Fig. 4) by one or the other of the tapered sides of a notch ⁴⁴ of inverted V-shape in the lower end of a bracket ⁴⁵ secured to the frame bar ³¹ and depending therebelow (Figs. 5 and 9).

It will be seen therefore that there has been provided a device for rapidly and accurately printing a varicolored design on a plurality of fabric pieces.

It is to be understood that a conventional individual squeegee may be used instead of the one illustrated in Fig. 10; furthermore, frame ³⁰ may consist of 3 separate silk screen members instead of the triple screen provided in this apparatus.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. Printing means for printing a selected design in different colors on individual pieces of fabric supported on platforms mounted in a circle about the periphery of a table rotatively supported on a stepped block mounted on a fixed bed plate, comprising a flat block mounted on top of the stepped block rotatively retaining the table in position on the stepped block, a single elongated printing frame pivotally mounted along one side to an adjacent edge of said flat block to be pivoted downward onto adjacent platforms at one side of the table, said frame being of a length to cover several platforms when pivoted downward, said frame being divided into a number of adjacent printing sections corresponding in number to the number of platforms covered by said frame when lowered, a printing screen embodying a portion of the selected design to be printed in one color stretched across each of said printing sections to rest down on the surfaces of the pieces of fabric mounted on

the platforms covered by said printing frame, means retaining said printing frame in a raised position off the platforms so that the table can be rotated to bring desired platforms into alignment with said printing frame, a pin extended radially outward from the outer edge of each of said platforms intermediate the side edges thereof, and a bracket depended from the side of said frame opposite its pivoted side, said bracket being located intermediate the ends of said frame and in alignment with the pin of the platform immediately below the center printing section of said printing frame, said bracket having an inverted V-shaped notch formed in its lower end to receive the pin of the platform centered below said printing frame for insuring that the table is in a proper rotative position in which the selected platforms are properly aligned with the printing sections of said printing frame in the lowered position thereof.

2. Printing means for printing a selected design in different colors on individual pieces of fabric supported on platforms mounted in a circle about the periphery of a table rotatively supported on a stepped block mounted on a fixed bed plate, comprising a flat block mounted on top of the stepped block rotatively retaining the table in position on the stepped block, a printing frame pivotally mounted along one edge of said flat block to be pivoted downward onto the platforms, said frame being of a length to cover several platforms when pivoted downward, said frame being divided into a number of adjacent printing sections corresponding in number to the number of platforms covered by said frame when lowered, a printing screen embodying a portion of the selected design to be printed in one color stretched across each of said printing sections to rest down on the surfaces of the pieces of fabric mounted on the platforms covered by said printing frame, means retaining said printing frame in a raised position off the platforms so that the table can be rotated to bring desired platforms into alignment with said printing frame, and means for insuring that the table is in a proper rotative position in which the selected platforms are properly aligned with printing sections of said printing frame in the lowered position thereof, said aligning means comprising a pin extended radially outward from the outer edge of each of the platforms, and a bracket depended from the outer side of said printing frame intermediate of the sides of said frame and in alignment with the pin of the platform below the center of said printing frame, said bracket having an inverted V-shaped notch formed in its lower end to receive the pin of the platform centered below said printing frame when said printing frame is lowered.
